UNITED STATES PATENT OFFICE.

HERBERT F. BABCOCK, OF RIFLE, COLORADO.

BEDSTEAD.

No. 823,152.

Specification of Letters Patent.

Application filed August 15, 1905. Serial No. 274,291.

Patented June 12, 1906.

To all whom it may concern:

Be it known that I, HERBERT F. BABCOCK, a citizen of the United States, residing at Rifle, in the county of Garfield, State of Colorado, have invented certain new and useful Improvements in Bedsteads; and I do hereby declare the following to be a full, clear, and exact description of the invention, such as will enable others skilled in the art to which it appertains to make and use the same.

This invention relates to bedsteads.

One object of the invention is to provide a bedstead embodying such characteristics that it may be readily converted into the single or double bedstead.

Another object of the invention resides in the provision of a simple, inexpensive, durable, and efficient bedstead of such nature that it may be easily collapsed to occupy small space or converted into a single or double bedstead.

With these and other objects in view the present invention consists in the combination and arrangement of parts, as will be hereinafter more fully described, shown in the accompanying drawings, and particularly pointed out in the appended claim, it being understood that changes in the form, proportion, size, and minor details may be made within the scope of the claim without departing from the spirit or sacrificing any of the advantages of the present invention.

In the drawings, Figure 1 is a top plan view of the bedstead. Fig. 2 is a view on line 2 2 of Fig. 1. Fig. 3 is an end view. Fig. 4 is an enlarged detail view illustrating the telescoping connection of the head portion of the bedstead. Fig. 5 is a view on line 5 5 of Fig. 1, illustrating the telescoping connection of the side rails.

Referring now more particularly to the accompanying drawings, the reference characters 1 and 2 designate the head-posts, the head-post 1 having upper and lower solid arms 3 and 4, connected by a series of vertical bars 5. The post 2 is provided with upper and lower hollow arms 6 and 7 for the reception of the solid arms 3 and 4 of the opposite head-post 1. The hollow arm 6 has its under face slotted, as at 8, while the lower hollow bar 7 has its upper face slotted, as at 9, adjacent which slots and connecting the said hollow arms is a series of vertical bars 10, corresponding to the aforesaid vertical bars 5, arranged between the solid arms 3 and 4.

Since the hollow arms 6 and 7 receive the corresponding solid arms 3 and 4, it will be understood that the posts 1 and 2 may be moved toward and away from each other, the arms 3 and 4 telescoping with the arms 6 and 7, the vertical supports 5 of the solid arms 3 and 4 passing through the said slots 8 and 9 of the hollow arms 6 and 7 when the head-posts 1 and 2 are moved toward and away from each other.

In order to facilitate the sliding movement of the arms 3 and 4 within the respective hollow arms 6 and 7, I enlarge the inner ends of the hollow arms 6 and 7, as at 11 and 12, respectively, and dispose a roller 13 at the top of the enlarged ends of said hollow arms and secure another roller 14 to the inner end of each of the solid arms 3 and 4. By reason of these rollers 13 and 14 friction is greatly reduced, and the solid arms 3 and 4 have a free sliding movement within the hollow arms 6 and 7.

Since the foot-posts 15 and 16 are provided with the same character of arms as the head-posts 1 and 2, it is thought that a detailed explanation of the foot of the bedstead is entirely unnecessary. However, reference to the drawings will disclose that the foot-posts 15 and 16 each have a hollow side rail 17 and 18, adapted to receive the solid side rails 19 and 20 of the head-posts 1 and 2, respectively. By reason of the telescopic arrangement of these side rails the head and foot board may be moved toward and away from each other, whereby the bedstead may occupy small space in transportation or in storing the same. It will be observed that the inner ends of the hollow members 17 and 18 are enlarged, as at 21, and each provided in its enlarged portion and at the top with a roller 22, which bears upon the upper face of the side rail sections 19 and 20 with each of the latter provided with a roller 22 depending therefrom for engagement upon the bottom of the hollow rail-sections 17 and 18. These rollers reduce friction and permit of a ready movement of the head and foot portions of the bedstead toward and away from each other.

My bedstead is preferably composed of iron or other suitable metal, and it will be seen that the hollow sections of the bedstead are of a D shape in cross-section. However, the hollow sections may be of any other form in cross-section, and so long as they slidably receive the solid sections of the bedstead it

will be understood that I do not limit myself to the particular form of hollow castings or sections illustrated in the drawings. The lower portion of the hollow rails 17 and 18 are each provided with a longitudinal slot 23 to receive inwardly-extending slat-supports 24, carried by the solid rail-sections 19 and 20 when the rail-sections are collapsed, there being slat-supports 25 carried by the inner face of each hollow rail-section adjacent its longitudinal slot 23. It will therefore be understood that the slat-supports 24 and 25, respectively, of the solid and hollow rails will not interfere with the collapsing movement of the head and foot portions of the bedstead toward and away from each other.

It is obvious from the foregoing that when the head and foot portions of the bedstead are moved toward each other the bedstead may be converted from a double into a single bedstead, and I will state that, if desired, the bedstead may be used as a crib or the like when the head and foot portions are moved toward each other.

What is claimed is—

A bedstead comprising head and foot portions including posts, one post of the head and foot portions each having upper and lower solid arms connected by vertical bars,

each upper and lower arm of said foot portions having a roller at its inner end, the opposite post of the head and foot portions each having upper and lower hollow arms for the reception of the corresponding upper and lower solid arms of the respective posts of the head and foot portions, the inner end of each of the hollow arms being provided with a roller for coöperation with the roller at the inner end of each of the solid arms to reduce friction when the solid arms are moved into and out of the hollow arms, the upper and lower hollow arms of the respective head and foot posts being connected by vertical bars, each upper hollow arm of the respective head and foot posts having a longitudinal slot in its under face and each lower hollow arm having a longitudinal slot in its upper face for alinement with the aforesaid slot whereby the aforesaid vertical bars connecting the solid arms may pass through the hollow arms and telescoping side rails connecting the head and foot posts.

In testimony whereof I affix my signature in presence of two witnesses,

HERBERT F. BABCOCK.
